UNITED STATES PATENT OFFICE.

WILLIAM A. PUGH, OF DADEVILLE, MISSOURI.

CLOTHES-PIN.

No. 886,245.

Specification of Letters Patent.

Patented April 28, 1908.

Application filed July 3, 1906. Serial No. 324,646.

To all whom it may concern:

Be it known that I, WILLIAM A. PUGH, a citizen of the United States, residing at Dadeville, in the county of Dade and State 5 of Missouri, have invented new and useful Improvements in Clothes-Pins, of which the following is a specification.

My invention relates to clothes pins, and its primary object is to provide a device of 10 this character adapted to be constructed of a single strand of wire and to be adjustably secured to a clothes line against accidental displacement.

A further object of my invention is to provide a clothes pin which is simple and durable, which will retain an article upon a clothes line against accidental displacement, and which may be manufactured and sold at a comparatively low cost.

With the above and other objects in view, the invention consists of the construction, combination and arrangement of parts hereinafter fully described, claimed and illustrated in the accompanying drawing, wherein:

Figure 1 is a side elevation, illustrating the application of my improved clothes-pin. Fig. 2 is a top plan view thereof. Fig. 3 is a section on the line 3—3 of Fig. 1, and Fig. 4 is an end elevation.

My invention is adapted to be constructed of a single strand of highly elastic wire treated to prevent rusting.

To form the clothes-pin, the strand is bent at a point intermediate its length to provide 35 a coiled expansion spring 2, through the medium of which the pin is adapted to be secured to a clothes line. After the spring 2 has been formed, the strand is extended laterally in both directions beyond the spring 40 to provide arms 3, which, when the pin is in applied position, are located below the clothes line. The strand is then bent upward at right angles to the arms 3 to provide arms 3^a, then bent to provide coiled contractile 45 springs 4 and thence bent downwardly to provide arms 4^a. The arms 3^a and 4^a, together with the springs 4, form clamps, the clamping members of which are firmly pressed against the clothes line to secure an 50 article thereon against displacement. The expansion of the spring 2 holds the arms 3

downwardly below the clothes line, thereby at all times retaining the clamping members in clamping position upon the clothes line. After the arms 4^a are formed, the strand is 55 bent inwardly towards the spring 2 to provide arms 5, which are bent inwardly in reverse directions to provide hook-members arranged within the spring 2 and consisting of vertical portions 6 and horizontal portions 7. 60

The clothes-pin is adapted to be secured to a clothes line by passing the line between the convolutions of the spring 2 at a point above the horizontal portions 7 of the hook-members 6, which prevent the accidental 65 displacement of the clothes-pin. The vertical portions of the hook-members 6 are disposed on opposite sides of the clothes line, for a purpose to be presently stated. When it is desired to secure articles to the clothes 70 line, the clamps are adapted to be disengaged from the clothes line by being moved upwardly, after which the articles may be positioned upon the line. After the articles have been properly positioned upon the line, the 75 clamps are released, whereupon the spring 2 moves the same downwardly into clamping position upon the line. The clamping members of the clamps are separated more or less according to the thickness of the articles, this 80 separation of the clamping members being limited by the engagement of the vertical portions of the hook-members 6 with the clothes line, whereby all liability of the horizontal portions 7 of the hook-members 6 being withdrawn from beneath the clothes line 85 and thus releasing the clothes-pin, is obviated.

From the foregoing description, taken in connection with the accompanying drawing, 90 the construction and mode of operation of the invention should be understood without a further extended description. Changes in the form, proportions and minor details of construction may be made within the scope 95 of the claims without departing from the spirit or sacrificing any of the advantages of the invention.

Having fully described and illustrated my invention, what I claim is:

A clothes-pin comprising an expansion spring adapted to receive a line, an arm form-

ing an integral part of the spring and adapted to be held below the clothes-line thereby, a clamp forming an integral part of the arm, and another arm forming an integral part of the clamp, said other arm having its end bent to provide a hook member disposed within the spring, the horizontal portion of the hook member being adapted to be disposed be-

neath the line and its vertical portion to one side thereof. 10

In testimony whereof, I affix my signature in presence of two witnesses.

WILLIAM A. PUGH.
